METHOD AND APPARATUS FOR PRODUCING CHORUS EFFECTS IN MUSIC

John M. Hanert, Park Ridge, Ill., assignor to Hammond Organ Company, a corporation of Delaware

Application April 27, 1951, Serial No. 223,376

21 Claims. (Cl. 84--1.24)

My invention relates to electrical musical instruments and more specifically to a novel means and method for producing the effect of a large chorus of instruments.

One of the most important and frequently-used musical or tonal effects is that of mass or chorus, as produced by a large number of musicians or tone producing instrumentalities playing or sounding in unison, for example, the first violin section of a symphony orchestra, or the many 8 ft. stops which may be simultaneously drawn on a large pipe organ. If these many tonal sources were exactly in tune, there would be no chorus effect and much of the musical charm resulting therefrom would be lost. It invariably happens, however, that the many musicians are unable to play exactly in tune and, in the case of the large organ, the many pipes are slightly out of tune with respect to each other. The highly desirable chorus effect is produced by these unavoidable small differences in pitch.

In an electrical musical instrument, the cost of the tone generating equipment is a substantial portion of the total cost of the instrument. In most instances, the provision of a large number of slightly detuned chorus generators is impractical and prohibitive in cost. This problem of generating chorus tones is an old one and many attempts have been made to solve it. One method has been to provide two or three slightly detuned tone-generating sources for each note of the scale, as shown, for example in Patent No. 2,159,505. Experience has shown, however, that when such a small number of chorus generators is provided, the effect produced must correspond to a relatively narrow and restricted chorus band.

Another effect has been obtained in organs by providing an intensity tremulant which, upon mathematical analysis, may be thought of as being productive of a "chorus" of side-band frequencies, as shown in Patent No. 1,956,350. However, this effect is not very satisfactory because the listener's ear does not acoustically interpret the phenomenon as being a chorus, but rather as an obtrusive and unmusical volume "shake" in the music.

Still another method has been to cause an over-all frequency or pitch modulation (vibrato) in the instrument, for example, as disclosed in my prior Patents Nos. 2,254,284 and 2,382,413. While these vibrato or frequency modulation systems result in tones which are far less obtrusive than the tremolo, because the energy of the tone is relatively constant, they nevertheless have the disadvantage that the discerning listener can easily hear the pitch of the tones rise and fall at the vibrato rate. In the true chorus effect, the energy as well as the pitch of the tones are perceived by the listener as being relatively constant.

An improved application of the vibrato principle to electrical musical instruments is disclosed in the patent to Laurens Hammond No. 2,276,389 wherein six different sources of vibrato modulating frequencies were employed in order to render the beat rate less obtrusive as the twelve successive semitones in the musical scale were sounded. Thus, for example, in the instrument shown in said patent

2

all the C and C[#] generators were modulated by one vibrato device, D and D[#] generators by a second vibrato device having a slightly different rate, etc. While by the use of the invention of said patent one succeeds in masking the vibrato repetitious effect, one can not produce any recognizable chorus effect over and above the condition where a unitary vibrato is employed on all the notes.

In the musical instrument of my invention, the illusion of a large chorus of players is created through a novel and simple acoustical principle. Briefly stated, this principle consists in causing electrical tone signal sources of substantially the same frequency (either as the fundamental or as a harmonic) to be provided with vibratos of opposite polarity or phase, so that as one source is modulated to a frequency above its nominal or average frequency, the other source will be simultaneously modulated to a frequency below the average frequency. When listening to both sources, the ear does not notice a change in frequency (as is the case with vibrato) because the average frequency of the tone is substantially constant. Since the energy in the output of each generator may be made to be relatively constant, there is no over-all tremulant effect in the tones of the instrument. If an oscilloscope is used in studying the superposition phenomenon which occurs upon combining two waves of the same or approximately the same frequency but of opposite vibrato polarity, one can observe a very complicated unsteadiness in the intensity envelope of the output signal. This unsteadiness in intensity is a characteristic of the chorus tone and occurs whenever the outputs of two or more tone generators having slightly differing frequencies are superimposed.

To produce a maximum chorus effect in a musical instrument, it should have two complex wave tone signal generators having the same fundamental frequency available for each note of the musical scale and a means for vibrato frequency-modulating each of these tone generators with opposing polarities. However, the chorus principle of this invention may also be applied with excellent results to instruments where there is but a single complex wave generator for each of the notes of the scale. In these instruments the even-numbered harmonics of the lower pitch are also generated as the fundamental and harmonics of the note one octave higher in the scale. If the vibrato for the lower note generator is made to be of opposite polarity, or 180° out of phase with respect to the vibrato for the generator having a pitch one octave higher, a very pleasing chorus effect is produced when these octavely-related generators are simultaneously sounded.

From the above it is seen that the primary object of my invention resides in producing the effect of a tonal chorus by frequency-modulating generators of substantially the same or octavely-related fundamental pitches in an opposing sense during a substantial portion of their modulation period.

A further object of the invention is to provide an improved electrical musical instrument capable of producing a desirable chorus effect from two tone signal sources of the same pitch by causing the sources to have oppositely phased vibratos.

A further object of the invention is to provide an improved electrical musical instrument in which several vibrato signals of different frequency, but within the vibrato range, are impressed upon different groups of generators of an electrical musical instrument, and thereby produce a desirable chorus effect.

A further object is to provide an electronic organ in which there are fewer oscillators than playing keys in the manual and in which the chorus effect is obtained by

applying oppositely phased vibrato controlling frequencies to alternate octaves of oscillators.

A further object is to provide an improved electrical musical instrument employing oscillators as sources of tone signals and to apply vibrato determining signals of different phases to successive octaves of oscillators, so that, when playing in octaves, the second harmonic of the lower pitched tone will have its vibrato out of phase with respect to that of the fundamental of the higher pitched octave tone and thereby produce a chorus effect.

Other objects will appear from the following description, reference being had to the accompanying drawings in which:

The invention now to be described in detail is of a fundamental character and is capable of embodiment in a large number of different forms, and it has not been attempted to illustrate in detail how the invention may be used in all its possible ramifications, but instead, typical applications of the principles of the invention to representative types of musical instruments are herein described and illustrated.

The general character of the invention may best be described by reference to Fig. 1 in which there is a source 20 of modulating vibrato frequency signals of opposite

25 phases, indicated as 0° and 180° . The apparatus represented by the block 20 is shown in Fig. 2 and will hereinafter be described in detail. Boxes 21 and 22 each represent an audio frequency source, for example, oscillators A and B generating complex tone signals of the

30 same nominal musical pitch, assumed to be $A=440, \pm 0.3$ percent. The term "nominal musical pitch" is used herein to mean a pitch which is closely associated with a particular note of the even tempered musical scale, and having a fundamental and harmonics in the audio frequency range extending from 32 c.p.s. to 15,000 c.p.s.

In practice the exact fundamental frequencies of the notes generated in the organ may drift considerably from their theoretically accurate pitch and, in fact, such deviations or inaccuracies in relative pitch are conducive to remove the unwanted "locking in" frequency effect which otherwise may occur between unisons (tones of the same nominal pitch), as well as between octaves related tone signal generators of complex wave form having low order integrally related fundamental frequencies.

A tone signal is "complex" when its low order harmonics are sufficient amplitude so that when the signal is translated into sound the harmonics have a readily noticeable effect on the quality of the tone as perceived by the listener. These two oscillators are independent

40 in the sense that the frequency of one does not control that of the other and may be of any suitable form, for example, of the type shown in Fig. 3 and hereinafter described. As will be described later with reference to Fig. 2 the vibrato frequency signals provided by the

45 apparatus 20 are of various phases, including 0° phase and 180° phase. The outputs of the oscillators are supplied to a common output system 23 which may include a speaker 25. Merely for purpose of illustration the oscillator A has its vibrato determined by the vibrato signal source 20 in the 0° phase whereas the oscillator B is provided with a switch 24 which when in full line position supplies the vibrato modulating frequency to the oscillator B at 180° phase and when in dotted line position supplies the oscillator B with zero phase vibrato signal.

Assuming that the switch 24 is in dotted line position the frequency of the signals produced by oscillators A and B will rise and fall together, at the same vibrato rate and to the same extent.

50 If the two sources 21 and 22 are exactly in tune, and generate pulses in-phase with each other, the effect of combining them is merely to cause an increase in intensity. If the two oscillators A and B happen to be slightly out of tune with respect to each other, the results of combining them are the same except for the addition of a slow phase-shifting effect as they "beat" in and out of

55 60 65 70 75 80 85 90 95

phase with each other. Depending upon their instantaneous relative phase, the resulting tone quality of the combined oscillator outputs will be heard to vary slowly over a wide range. At times, the combination tone will even sound at the interval of the octave (if the generators produce pulses of like polarity) or will pass through a period of silence (if the generators produce pulses of opposite polarity). Introduction of a vibrato of like polarity in the tones of the two generators is found to have no beneficial effect whatsoever on this difference beat phenomenon, but rather tends to magnify the effect and produces a most unnatural "whining" effect. This "whining" effect is unmusical because it has a peculiar unsteady effect which suggests the sound heard over short-wave radio when listening to stations at great distances over changing sky wave paths. This "whining" effect is also heard to a lesser, but nevertheless disturbing, extent when tones, having vibratos of like polarity, an octave apart are played.

If, however, switch 24 is moved to its full line position so that the modulating vibrato frequency is impressed upon oscillators A and B in opposite phase, an entirely different and novel effect is obtained. The tone signals from the two oscillators will then vary in frequency in the manner indicated in Fig. 15, that is, one of the oscillators will be generating a frequency higher than the nominal frequency while the other oscillator is generating a frequency lower than the nominal frequency. In Fig. 15 the shape of the curves 26 and 28 is not of particular significance. The modulating frequency may be of a sine wave form or square wave form or any intermediate form. It will be understood that the curves 26 and 28 indicate merely the instantaneous frequencies of the oscillators A and B respectively.

When the vibrato frequencies applied to the oscillators A and B are of opposite phase or polarity, this undesirable "whining" effect disappears and a most realistic and musically attractive illusion of a chorus of instruments is produced. The pleasant tonal animation makes it almost impossible to perceive the "beat" caused by the difference in the average pitch of the two generators. This desirable "masking" of the difference "beat" is so great that it becomes virtually impossible to tune the oscillators to the same pitch while the chorus phenomenon is being produced. The extent of the chorus effect is controlled chiefly by the extent of the vibrato.

The reason for the disappearance of the "whining" effect lies in the fact that the two oscillators are always being frequency-modulated in opposite senses which makes it impossible for them to remain in any particular phase relation for a period of time more than a fraction of the vibrato period. It is interesting to note that the rate of the vibrato in the tones generated by the two sources may be varied without the listener being particularly aware of any change. Thus, the vibrato is being used purely as a means or mechanism for maintaining an illusion of chorus when the two tone generators are simultaneously sounded.

Assuming that the oscillators A and B are generators of complex tone signals, the frequencies of their harmonics will vary in the same manner as the frequencies of their fundamentals so that the chorus effect is present in all of the partials as well as in the fundamental.

The effect of moving the switch from its dotted line to its full line position is startling. In the dotted line position one hears what appears to be but a single tone signal source modulated by a vibrato frequency and if the sources are not of exactly the same frequency the above mentioned whining effect will be present, whereas, with the switch 24 in the full line position, one hears what is apparently a very large number of signal sources sounding simultaneously, namely, a full chorus and the vibrato effect is hardly noticeable. By constructing a simple apparatus of the type shown in Fig. 1 the musical

desirability and value of the chorus effect may be demonstrated.

This chorus effect may be obtained by frequency modulating the two tone signal sources at different rates as diagrammatically illustrated in Fig. 1a. This method, however, is only about half as efficient as that described above. In Fig. 1a it is assumed that the oscillators 21 and 22, the output system 23, speaker 25, and switch 24 are of the character above described with reference to Fig. 1.

The source of modulation signals 20A is, in fact, two sources of different frequencies, for example, 4 and 8 c.p.s., this apparatus being shown in detail in Fig. 2a. When the switch 24 is in its dotted line position the same non-chorus effects will be obtained as described under the corresponding condition with reference to Fig. 1. However, when the switch 24 is moved to its full line position the two oscillators will be frequency modulated in the manner represented in Fig. 17 wherein the dash line curve 26A represents the instantaneous frequency of the output of the oscillator A while the full line curve 28A represents the instantaneous frequency of the oscillator B. For the particular modulating frequencies selected for illustration, the chorus pattern repeats four times per second. The chorus effect is better if the modulating frequencies do not have a common integral factor (other than 1) e.g. 5 and 7 c.p.s. so that the chorus pattern repeats every second.

From Fig. 17 it will be apparent that the two oscillators have their frequency modulation of opposite polarity during only one half of the time, while during the remaining half time they are of the same polarity. Thus the chorus effect is obtained during only half the time that the tone is sounded, that is, during the time intervals indicated by the double headed arrows A and B. This method of frequency modulation produces results which are a substantial improvement over those of the prior art with respect to the simulation of a chorus. The frequency modulating rates 4 and 8 were selected because of the simplicity of the diagram of instantaneous frequencies (Fig. 17) but other modulating frequencies may be employed, the more desirable modulating frequencies lying within the range of from 3 to 10 c.p.s. Higher modulating frequencies, such as high as 15 c.p.s. may be used, but to most persons the chorus effect becomes less desirable. The diagram of Figs. 1a and 17 thus further illustrate the breadth of the fundamental principle of the invention.

As previously indicated, the invention may be embodied in a wide variety of musical instruments, and some of the different possible forms of instruments in which the invention may be utilized are illustrated in the drawings.

In general, most of these instruments employ one or more oscillators which may be of any well-known type but which preferably are of the type shown in Fig. 3, or of the type shown in Fig. 3a. In Fig. 3 the oscillator comprises a triode 30 having an adjustable tuning circuit including a capacitor C32 and a variable inductance L34 connected between a terminal S and a terminal 36. The terminal 36 is connected to the control grid 38 of triode 30 through a capacitor C40. The cathode 42 is connected to a tap on the inductance L34 while plate 44 is connected to a terminal K through an attack resistor R46 which has a resistor R48 and capacitor C50 in series across its terminals. The plate 44 is connected to ground through an attack capacitor C52. The control grid 38 is connected to a terminal V through a decoupling resistor R54 while the terminal 36 is connected to a decoupling resistor R56 to a terminal F.

The terminal V will be connected to one of the terminals 121, 122, 124 to 127 of the vibrato apparatus (Fig. 2) depending upon the manner in which the oscillator is to be used, as will appear hereinafter.

The frequency of oscillation of the oscillator 30 may

be decreased three semitones by connecting a capacitor C58 between the cathode and terminal S and for this reason the capacitor C58 is shown as connected between cathode 42 and a first tuning terminal T1 so that by a switching means, not shown in Fig. 3, T1 may be connected to S whenever it is desired to lower the pitch of the oscillator by three semitones. In a similar manner the pitch of the oscillator may be lowered a full tone by connecting a capacitor C60 in series with C58 by connecting a terminal T2 to the terminal S. The pitch of the oscillator may be lowered one semitone by connecting a third capacitor C62 in series with C58 and C60, this being accomplished by connecting a terminal T3 to the terminal S.

The oscillator shown is adapted to be keyed (rendered operative) by supplying plate voltage to the terminal K and will have its frequency shifted to introduce the vibrato effect by having a vibrato frequency signal impressed upon the terminal V. The signal which appears upon the terminal F is of flute-like character, that is, it is substantially sinusoidal. On the other hand, the signal appearing at the terminal S will be very complex and rich in harmonics so that, by the use of suitable filtering meshes, tone qualities of the string and reed families may be derived therefrom.

In such forms of the invention in which the signal is to be keyed, requiring a continuously operating tone signal generator, the oscillator shown in Fig. 3a may be employed. This oscillator comprises a triode 70, the control grid of which is connected to the V (vibrato) terminal through grid resistor R54.

The plate of the triode 70 is connected to ground through a filtering capacitor C53 and is connected to a B+ terminal through a load resistor R72. The cathode 74 is connected to a tap on a variable inductance L76 which has a capacitor C78 in parallel therewith. One end of the resonant circuit provided by L76 and C78 is connected to the grid of the triode 70 through a capacitor C80. The other terminal of the resonant circuit is connected to ground through a resistor R82 which has a resistor R84 in series with a capacitor C86 in parallel therewith. A secondary winding L88 is coupled to the inductance L76 and is connected between ground and a terminal F1 to provide a tone signal of flute-like quality. The string-quality signal is derived from a terminal S1 which is connected to the junction of C86 and R84.

The apparatus for producing vibrato modulating frequencies of several different phases is shown in Fig. 2 as comprising a phase shift oscillator 90 consisting of a triode 92 the cathode of which is connected to ground and the plate of which is connected to a B+ terminal of the power supply through a load resistor R94. A multi section phase shifting mesh is connected between the plate and grid of the triode 92 and comprises a plurality of series capacitors C96, and shunt resistors R98. Each of the resistors has one end connected to a -2.5 v. terminal and its other end connected to one of the junctions between capacitors C96. This phase shifting mesh has terminals 100 to 105 at which the signal appears in different phases. Terminal 105 is connected to the grid of triode 92 by a resistor R106. Assuming that the phase of the signal produced by the oscillator 90 is 0° at its plate and at the terminal 100, the phase of the signal at the terminal 101 will be 60°, that at terminal 102 will be 90°, and that a terminal 103 will be 120°.

In order to amplify and produce several signals of different phases from the signal appearing at terminal 100, the latter is connected through a decoupling resistor R103 with the grid of a switching triode 110. This triode is supplied with plate current through a suitable load resistor R111 connected to a B+ terminal. The cathode of triode 110 is connected to a -4.5 v. terminal by resistor R112 having a bypass capacitor C114 in parallel therewith. The plate of triode 110 is connected to a terminal

119 and the phase of the signal appearing at this terminal is, of course, opposite to that on the grid of the triode 110, namely, 180°. The signal on the cathode is, of course, of the same phase as that on the grid and this signal of 0° phase thus appears upon a terminal 122 connected to the cathode of triode 110.

A triode 116 has its input circuit coupled to the plate circuit of triode 110 through a blocking capacitor C118 and a series grid resistor R130. The junction of C118 and R130 is connected to a -4.5 v. terminal through a grid return resistor R132, and the cathode is connected to this terminal through a resistor R134 having a capacitor C136 in parallel therewith. Plate current is supplied through a plate load resistor R138 connected to a B+ terminal. The plate is connected to a terminal 120 while the cathode is connected to a terminal 121 to provide signals of 0° and 180° phase, respectively.

Terminal 101 of the phase shift network is connected to the grid of a switching triode 140 through a decoupling resistor R142, and the output of triode 140 is coupled to the input of a triode 144 in the same manner that the triode 116 is coupled to the triode 110. The signal appearing at the plate of triode 140 and the signal at the cathode of triode 144 have a phase angle of 240° 25 and these signals are impressed upon output terminals 123 and 124.

The terminal 102 of the phase shift network of the oscillator 90 is connected to the input of a triode 150 which is coupled to a triode 152 in the same manner that the triodes 140 and 144 are coupled, and the output of the triode 152 is impressed upon the input circuit of a triode 154 which is similar to the triode 116 and is provided with similar circuit components. The cathode of triode 154 is coupled to an output terminal 125 while the cathode of triode 152 is connected to an output terminal 126. Since the signal on terminal 102 has a 90° phase, that appearing on the cathode of triode 152 will be of 270° phase and the signal appearing on the cathode of triode 154 will be of 90° phase.

The terminal 103 of the phase shifting mesh of the oscillator 90 is connected to the input of a triode 160, the output of which is coupled to an amplifying triode 162. The output of triode 162 is coupled to the input of a triode 164 and the latter has its cathode connected to an output terminal 127. Since the signal at terminal 103 has a phase of 120° the signal on the cathode of triode 164 will also be of 120° phase.

It is not contemplated that the vibrato oscillator and amplifying circuits of Fig. 2 shall be used in the form shown for any particular instrument. Instead, it is intended that this oscillator, and such of the amplifying apparatus as may be required for a particular instrument, be used and the remaining parts omitted. For example, the signals appearing on terminals 119, 120, and 123 are required only for the type of oscillator shown in Fig. 4. In many instruments it is necessary to have the vibrato frequency available in only two opposite phases so that the circuits associated with triodes 110 and 116 are the only ones that would be required and it would be necessary for the vibrato apparatus to have only two terminals such as 121 and 122 (in addition to a ground terminal) for such instruments.

The oscillator 90 preferably oscillates at approximately 7 cycles per second (c.p.s.) although in some forms of the invention disclosed herein it is required that several such oscillators be provided and that they oscillate at slightly different frequencies.

A similar pair of sources of frequency modulating signals may be derived from the apparatus shown in Fig. 2a and which may be employed in the manner above described with reference to the method diagrammed in Fig. 1a. In Fig. 2a triodes 92A and 92 are provided with phase shifting networks coupled to their grids in the same manner as above described with reference to the oscil-

lator of Fig. 2, with the exception that these networks have fewer sections to produce the required 180° phase shift. The outputs of the oscillator triodes 92A and 92B are suitably coupled to the input of switch tubes 94A and 94B. The switch tube 94A has its plate connected to a terminal 119A, which in a certain sense corresponds to the terminal 119 of Fig. 2. The triode 94B has a cathode resistor R95 and the signal across this resistor is utilized for frequency modulating the types of oscillators shown in Figs. 3 and 3a, by having the V terminal of the oscillator connected to terminal 121A, which is connected to the cathode of triode 94B. The terminal 121A corresponds in general with the terminal 121 of Fig. 2.

Fig. 4 shows representative portions of a melody instrument, comprising an oscillator including a pair of triodes 170 and 71 driving a triode 172. The frequency of oscillation of this oscillator, is determined by a plurality of capacitors C176 connected between the grid of triode 170 and ground, and a plurality of inductance elements L178 which are connected in series between the grid of triode 170 and ground. The number of the inductance elements L178 which are effective is determined by switches 180 which are adapted to connect the junctions between successive inductance elements to a grounded conductor 181 upon operation of playing keys 183.

A number of coarse and fine tuning capacitors C182 are adapted to be connected between the grid of triode 170 and ground by means of switch members 184, initially to tune the instrument.

Whenever it is desired that the oscillator 170, 171 produce a vibrato, one or both of a pair of switches 186 is moved to its full line position, thereby effectively to connect one or both of different value capacitors C187 between the grid of triode 170 and a conductor 189. The conductor 189 is adapted to be connected to terminal 119, 120, or 123 of the vibrato apparatus shown in Fig. 2, or to terminal 119A of Fig. 2a. It will be noted that these terminals are connected to the plates of triodes 110, 116, and 140 of Fig. 2, or triode 94A of Fig. 2a, respectively, and that these triodes operate effectively as a switch to connect conductor 189 substantially to ground potential and thus place one or both of the capacitors C187 effectively in the tuning circuit of the oscillator 170, 171 during substantially one half of each vibrato cycle. When the switches 186 are in dotted line position they connect compensating capacitors C185 in the tuning circuit of the oscillator and these capacitors have values respectively about one half those of the associated capacitors C187 so that when the oscillator 170, 171 operates without vibrato its frequency will be the average of the frequencies at which it operates under vibrato conditions.

In addition to operating the switches 180 the playing keys 183 operate switches 190 to connect a conductor 192 to ground, as will hereinafter appear. The wave front of the signal produced by the oscillator 170, 171 is made more steep by the triode 172 and is impressed upon a pulse sharpening and rectifying triode 194, the output of which supplies sharp negative pulses to the grids of alternate pulse responsive triggering triodes 196 and 197, which operate as the first stage of a frequency divider. Several cascaded stages of frequency divider circuits may be provided, each operating to divide the input frequency by two. Signals are derived from each of these stages as well as from the rectifier triode 172 and oscillator triode 170 through suitable coupling meshes which optionally may be connected to an output collector conductor 200 upon selective operation of switches 202 by stop tablets or the like. The signals appearing between the conductor 200 and ground are supplied to suitable tone quality controls 204, which may be in the form of a number of different filtering meshes, and the signal thus modified, in transmitted through transformer 206 in push-pull to the grids of a pair of control triodes 207, 208. These triodes are normally biased

beyond cut off by having their cathodes connected through resistors R209 and R210 to a +250 v. terminal. Resistor R210 together with a resistor R211 form a voltage divider. The junction of these resistors is connected to conductor 192 so that when one of the switches 190 is closed the potential on the cathodes of the control triodes 207 and 208 is reduced substantially to ground potential, and thus render these triodes conductive, the rate of attack and decay being controlled mainly by the values of R210, R211, C214, and C216. The control triodes 207, 208 are coupled by a transformer 218 to a power amplifier 220 which supplies a speaker 222.

Briefly, the section of an instrument shown in Fig. 4 operates in the following manner: Closure of one of the switches 180 by depression of a playing key 183 higher than any previously depressed key will tune the oscillator 170, 171 to a frequency the same as or octavely related to the nominal pitch of the depressed key, and the several stages of frequency dividers will operate to provide frequencies successive octaves lower than that which the oscillator 170, 171 is tuned. After the closure of switch 180 the switch 190 is closed to render the control triodes 207 and 208 conductive of the signal, with a suitable rate of attack and decay. Upon release of a depressed key 183 its switch 190 opens to permit the potential on the cathodes of the control triodes 207 and 208 to rise to a cut off value, and thereafter, upon opening of the switch 180, the oscillator 170, 171 will be tuned to its lowest frequency since all of the inductance elements L178 will be effectively in the oscillator tuning circuit. The family of tone qualities, as well as the pitch range desired, is controlled by selective operation of the switches 202 as well as by operation of the various tone quality controls 204. An over-all volume control of any suitable construction may be included in the input stage of the power amplifier 220.

Having described the construction and operation of most of the essential sections of electrical musical instruments, the manner in which the invention may be incorporated in complete instruments will now be described.

A very satisfactory type of instrument may be constructed in the manner shown in Fig. 5, wherein a melody section 230, which may be of the general construction shown in Fig. 4, is combined with a single manual organ section 231 comprising 37 oscillators of the kind shown in Fig. 3 or the kind shown in Fig. 3a. The melody section will have its conductor 189 connected to terminal 119 of the vibrato apparatus of Fig. 2 while the V terminals of all of the oscillators of the organ section are connected by a conductor 232 to the terminal 122 of the vibrato apparatus of Fig. 2. (As a less desirable alternative, the conductors 189 and 232 may be connected to terminals 119A and 121A, respectively, of the apparatus shown in Fig. 2a.)

All of the terminals F of the oscillators are connected to a terminal 234 while all the S terminals of the oscillators are connected to a terminal 236. Thus by operation of a switch 238 tone signals of the flute family will be supplied to a preamplifier 240 through a decoupling resistor R242, and similarly upon closure of a switch 239 tone signals of the string family will be transmitted to the preamplifier 240 through a resistor R243. The preamplifier 240 is coupled to a power amplifier 220 which supplies its output to a speaker 222. As in the previous instance the power amplifier may include a suitable volume control device in its input circuit.

It will be clear that in the instrument shown in Fig. 5 the signals produced in the melody section 230 will have a vibrato of 190° phase whereas the signals produced by the organ section 231 will have a vibrato of opposite polarity or 0° phase, and that as a result a rich chorus effect will be obtained when both sections are used at the same time. The chorus effect is most pronounced when the pitch, loudness, and quality of the solo and organ sections are the same. It will be understood that

the keys of the organ section ordinarily will be designed to operate the key switches of the melody section as well as those of the organ section.

The invention may be applied to an instrument having but a single rank of generators or oscillators and this is accomplished as shown in Fig. 6. In this instrument the oscillators for the first, third, and fifth octaves will have their V terminals connected to terminal 121 of the vibrato apparatus; while the oscillators for the tones of the even numbered octaves have their V terminals connected to the terminal 121 of the vibrato apparatus. These oscillators may be either of the type shown in Fig. 3 or the type shown in Fig. 3a and the instrument is provided with the usual manual controls, amplifier, and speaker indicated by the block 250. By thus connecting alternate octaves to oppositely polarized terminals of the vibrato apparatus many of the advantages of the invention are obtained, although the underlying principles of the invention are not utilized to the maximum extent. In an instrument such as shown in Fig. 6 the fundamental frequency of a tone in one octave will have its vibrato oppositely phased with respect to the second harmonic of a tone an octave lower in the musical scale. Since the second harmonic is of substantial intensity in most musical tone qualities, and since the fundamental frequency of the higher octave note is of the same, or substantially the same pitch as the second harmonic of the lower octave note, a very pronounced chorus effect will be produced by these two generators because their vibratos are oppositely polarized. In a large proportion of music the octave intervals appear frequently, so that the use of the invention in the manner shown in Fig. 6 is of substantial value in greatly improving the over-all musical results by the addition of the chorus effect.

A very desirable form of melody instrument may be constructed by using two melody sections such as shown in Fig. 4, combining them in the manner shown in Fig. 7. The first melody section 260 has its conductor 189 connected to the terminal 119 of the vibrato apparatus shown in Fig. 2 whereas the second melody section has its conductor 189 connected to the terminal 120 of the vibrato apparatus. The two sections may have a manual 259 and a common output system 262. The latter includes the various controls, amplifier, and speaker. The tuning and control switches of both sections are operated by the keys of the single manual 259. The chorus effect in an instrument of this character is very desirable because a musician can produce tones which are perceived by auditors as coming from a section of a symphonic orchestra. For example, by using the string tone qualities the musician can produce music comparable to that produced by the symphonic string section, and similarly, by an adjustment of the tone quality controls, can perform as a substitute for the horn section, the oboe section, etc.

In applying the invention to a two manual instrument having two independent groups of oscillators for generating the tone signals the arrangement may be of the type illustrated in Fig. 8, wherein block 266 represents an oscillator such as shown in Fig. 3 for the notes C1 and C1 $\sharp$; the block 267 represents the oscillators for the notes D1 to B1; the block 268—the oscillators for the notes C2 to B2; the block 269—the oscillators for the notes C3 to B3; the block 270—the oscillators for the notes C4 to B4; and the block 271—the oscillators for the notes C5 to B5.

It will be noted that upon closure of switches 274 and 275, by means of a suitable control tablet 276, the V terminals of alternate octaves of oscillators will be connected to the terminal 122 of the vibrato apparatus while the intermediate octaves of oscillators will have their V terminals connected to the terminal 121 of the vibrato apparatus. Similarly the oscillators and generators for the lower manual, upon closure of switches 278 and 279 by tablet 280, will have the V terminals of alternate octaves of oscillators connected to the terminal 75

121 of the vibrato apparatus and the oscillators of the intermediate octaves will have their V terminals connected to the terminal 122 of the vibrato apparatus. Upon depression of a key such, for example, as C1, switch 282 closed thereby will connect the K terminal of the oscillator such as shown in Fig. 3 to a B+ terminal thus supplying plate current to render the oscillator operative. The C1 key, in addition to closing a switch 282 to render the oscillator operative, closes a switch 284 thereby connecting the T3 terminal of the oscillator to its S terminal and, by including the capacitors C58, C60, and C62 (Fig. 3) in the oscillator tuning circuit, decreases the pitch at which the oscillator operates by one semitone. When the tablets 276 and 280 are not depressed the switches operated thereby connect the "V" terminals to ground.

If an oscillator is provided for each pair of adjacent semitones a switch such as 284 must be provided to tune the oscillator a semitone lower than its normal frequency of oscillation, whereas if an independent oscillator is employed for each semitone the keys need to operate only one switch such as the switch 282.

In an instrument of the type shown in Fig. 8 all of the F terminals of all oscillators may be connected to a common conductor 286 and all of the S terminals connected to a common conductor 288. The conductor 286 is adapted to be connected to various tone controls 290 upon closure of a flute tone selecting switch 292, while if string quality tones are desired a switch 294 is closed. It will be noted that the conductor 288 is connected to ground through a relatively low value resistor R296 and is connected to the switch 294 by a mesh comprising a series capacitor C295 and resistor R296, the latter having a capacitor C297 in parallel therewith. In a similar manner the output of all of the oscillators for the lower manual are supplied to suitable tone controls 299, the signals as modified by the controls 290 and 299 being supplied to preamplifier 300 which feeds a power amplifier 302, the latter including an over-all volume control 40 and supplying a signal to a speaker 303.

In the instrument shown in Fig. 8 playing of octave notes on either manual results in the production of the chorus effect between the fundamental of the higher note and the second harmonic of the lower note. If unison notes are played on both manuals the two tones produced will also have oppositely polarized vibratos and the chorus effect will result.

The advantages of the invention may be obtained in the instrument shown in Fig. 9, but at considerable cost. In this instrument there are two sets of master oscillators 310 employed to provide a controlling signal to cascaded frequency dividers 312, for example, in the manner disclosed in the patent to Laurens Hammond 2,126,682 granted August 9, 1938. Any other suitable circuit arrangement may be employed in which master oscillators control the frequency of a series of dividers extending through a range of four or five octaves, to provide the tone signals for the manuals and pedals. The outputs of these frequency dividers, under the control of the usual manuals and pedals is supplied to box 314 which represents the preamplifier, tone quality, volume, and reverberation controls, the power amplifier, and the speaker.

The master oscillators 310 may be of any suitable construction but herein will be assumed to be of the type shown in Fig. 4, each having an input conductor 189 for connection to a vibrato switch tube. The conductors 189 for one group or set of master oscillators are connected to terminal 119 of the vibrato apparatus of Fig. 2 whereas the conductors 189 of the second group of master oscillators are connected to the terminal 120 of the vibrato apparatus. If the master oscillators are of a type in which the vibrato effect is obtained by impressing a vibrato frequency upon the control grids (as for example the oscillator in Fig. 3) then the V terminals

of such oscillators should be connected to terminals 121 and 122 of the vibrato apparatus.

The key operating switching means of the instrument shown in Fig. 9 is such that a signal from each group of master oscillators or each group of frequency dividers is transmitted to the output system upon operation of a single key. Thus depression of any key will result in the transmission to the output system of two signals of the same pitch (and preferably of the same or similar quality) but having oppositely phased vibratos, and as previously explained, this will be perceived by the listener as a rich chorus tone.

While the application of the invention to an instrument of the type employing master oscillators and cascaded frequency dividers requires substantial duplication of the tone signal generating apparatus, this additional cost is well justified by the greatly enhanced beauty of the music capable of being rendered, due to the addition of the chorus effect.

The invention may also be applied to very large and complicated organs employing several ranks of tone signal generators for each manual. Such an instrument is diagrammatically represented in Fig. 10 as having four six-octave ranks of generators for each of the manuals. The octave groups 320 of tone signal generators are connected to different terminals of the vibrato apparatus in a manner to produce a maximum chorus effect.

The generators of the signals used mostly on the upper manual are indicated as Diapason, 8', f; Cornopean, 8', mf; Salicional, 8', mp; Violin, 4', mp. The generators of tone signals used mostly on the lower manual are indicated as Open Diapason, 8', ff; Chimney Flute, 8', mf; Harmonic Flute, 4', mf; Dulciana, 8', pp.

The Diapason, 8', f has the V terminals of its odd numbered octaves of generators (assuming the generators are oscillators of the form shown in Fig. 3a) connected to the terminal 121 of 180° phase while its even numbered octave groups 320 are connected to the terminal 122 of the vibrato apparatus of 0° phase. The Cornopean rank has the vibrato terminals of its odd numbered octave groups connected to terminal 122 and its even numbered octave groups connected to terminal 121 so that, for example, if the Diapason and Cornopean stops are used at the same time the signals provided by these ranks of generators will be modulated in opposite phase.

The Salicional, 8', mp rank has even numbered octave groups connected to terminal 125 (90° phase) while the vibrato terminals of its odd octaves are connected to the terminal 126 (270° phase). Thus if the octave notes are played using the salicional rank the vibratos on the two notes will be oppositely phased, and a chorus effect obtained between the second harmonic of the lower note and the fundamental of the higher note.

The rank of generators for producing violins, 4', mp, have their corresponding octave groups of generators modulated in opposite phase with respect to the salicional groups so that if these two ranks of generators are employed simultaneously an excellent vibrato chorus will result. Also because the successive octave groups of generators of the violin, 4' rank are modulated in opposite phase a certain degree of vibrato chorus will result in the manner above explained.

The open diapason, 8', ff rank of generators have successive octaves provided with oppositely phased vibratos by having their vibrato terminals connected to the terminals 122 and 121 of the vibrato apparatus of Fig. 2, while the chimney flute, 8', mf has its octave groups of oscillators phased oppositely to those of the open diapason.

Similarly the harmonic flute, 4', mf rank of generators has its successive octaves oppositely phased by having their vibrato terminals connected to terminals 122 and 121 of the vibrato apparatus. The dulciana, 8', pp rank has alternate octave groups of generators connected to

terminals 125 and 126 of the vibrato apparatus thus making the vibrato on adjacent octave groups of opposite phase.

By thus phasing the vibratos impressed upon the various octave groups of generators, it is highly probable that the organist will select generators from different ranks which are oppositely phased or which at least are not in phase. In this way the advantages of the chorus effect are obtained when playing with the more commonly used registrations and are attained in a large measure even when unusual registrations are employed by the organist, or when but a single rank of generators is being used.

As fully explained in the patent to Laurens Hammond No. 2,276,389 there are advantages in utilizing different vibrato rates on the tone signal generators for the twelve semitones of the musical instrument, so that when a chord is played the different notes will not rise and fall in frequency at the same rate and thus the undesirable effect of over-all vibrato periodicity is obviated. But in the instrument described in said patent all octavely related notes were vibrato modulated at the same rate and in phase so that no chorus effect could be obtained between the second harmonic of the lower note and the fundamental of the note an octave higher in the scale.

The desirable vibrato chorus effect may be obtained while retaining the advantages of this invention by employing the apparatus shown in Fig. 11 wherein different generators 330 are controlled by vibrato modulating frequencies of various rates. The vibrato apparatus of Fig. 2 may be duplicated except for slight changes in the circuit constants so that one vibrato apparatus 332 will provide a modulating signal of 5.5 c.p.s., the next vibrato apparatus 333 operates at 5.8 c.p.s., and the vibrato apparatuses 334 to 337 producing vibrato modulating signals at 6.1, 6.4, 6.7, and 7.0 c.p.s. respectively. Adjacent semitone generators 330, which are seldom used at the same time, are connected to the same terminal of one of the vibrato signal producing apparatuses 332 to 337. For example, generators 330 for the notes C1 and C1# are connected to the terminal 121, generators for notes D1 and D1# connected to the terminal 121 of a second vibrato apparatus 333, the generators for notes E1 and F1 connected to the terminal of vibrato apparatus 334 etc. The next octave of generators, for example, the generators 330 for the notes C2 and C2# are connected to the terminal 122 of the vibrato apparatus 332 so that these generators will have their vibrato oppositely phased with respect to the generators an octave lower. The third and fifth octave generators would be connected in the same manner as the lowest octave generators while the fourth and sixth octave generators would be connected in the same manner as the second octave generators. The generators 330 may be keyed in the manner shown in Fig. 8 and may have their outputs transmitted to the output system in the same manner as shown in said figure, or in any other suitable way.

In a simple type of organ having but one set of generators the vibrato modulating frequency may be employed to obtain some chorus effect in the manner indicated in Fig. 12, wherein the first, third, and fifth octave groups of generators 340 have their vibrato terminals connected to the terminal 121 of vibrato apparatus 342 generating a vibrato frequency of 5.5 c.p.s., whereas the intermediate octave groups of tone generators have their vibrato terminals connected to a terminal 121 of a vibrato apparatus 343 operating at 6.5 c.p.s. The vibrato apparatus 342 and 343 may be identical with that shown in Fig. 2 except that the constants will be such as to produce the slightly different modulating frequencies. While the use of different vibrato rates, as illustrated in the examples of Fig. 12, is not as satisfactory as having the vibratos of the same rate but of opposite phase, this arrangement nevertheless utilizes in a substantial measure the underlying principles of the invention

because at any particular instant there will usually be a substantial number of partials of the tones which are sharp relative to the nominal frequency and another substantial number which are flat relative to the nominal frequency, thus producing a substantial chorus effect.

The invention may be embodied in an instrument of relatively low cost in the manner shown in Fig. 13, wherein the oscillators are of the type shown in Fig. 3 capable of generating any one of four adjacent semitone frequencies. In Fig. 13 the oscillators 350, of the type of Fig. 3, are shown as each capable of providing the four adjacent semitone signals except for the oscillators at the ends of the keyboard which need to cover ranges of only one, two or three semitones. The oscillators are under the control of keys 354, each of which operates three or four switches including at least one switch 355 and one switch 356 for connecting the keying terminals K of adjacent oscillators 350 to a B+ terminal and including at least one tuning switch 358 to connect one of the terminals T1, T2, or T3 to either a conductor 359 or conductor 360, thereby to tune one or two adjacent oscillators to the required frequency.

The frequencies capable of being generated by the various oscillators 350 are indicated in the drawing by the note designations. By tracing the circuits it will be observed that depression of any key results in causing two adjacent oscillators 350 to generate notes of the same pitch, and that such two adjacent oscillators which are capable of producing tone signals of the pitch called for by an operated key, also have their K terminal connected to the B+ terminal so as to render them operative. The vibrato terminals of alternate oscillators 350 are connected to the terminal 121, and the intermediate oscillators are connected to the terminal 122, of the vibrato apparatus of Fig. 2. Thus, whenever a key is depressed, two adjacent oscillators will be rendered operative and these two adjacent oscillators will have vibratos of opposite phase impressed thereon so as to produce a full chorus effect.

The S terminals of all of the oscillators are connected to conductor 362 (to which conductors 359 and 360 are also connected) while the F terminals of all the oscillators are connected to a conductor 364. Under the control of optionally operable switches 366 and 367 tone signals of desired string-like or flute-like quality, or both, are transmitted to the output system. In Fig. 13 the output system is illustrated as comprising tones controls 368 coupled to a preamplifier 370 which transmits the signals to a power amplifier 372 for energizing a speaker 374.

The invention may be incorporated in an organ having conventional coupler switching mechanisms between the manuals and the generators, such type of instrument being represented in Fig. 14 as having an upper manual 380 and a lower manual 382 each being capable of being coupled to one or both sets of signal generators 384 and 386 by operation of coupler switch mechanisms 388. In addition the upper manual may be arranged to control the sounding of a melody tone signal generator 390 of the type shown in Fig. 4. The generator sets 384, 386, and 390 may each have individual tone and volume controls 392 coupling their outputs respectively to an overall volume control and amplifier 394, feeding into a speaker 396.

The chorus effect is obtained in the instrument shown in Fig. 14 by connecting the vibrato terminals V of the odd numbered octave groups of generators 384 to terminal 122 (0° phase) of the vibrato apparatus while the corresponding vibrato terminals of the even numbered octave groups are connected to the terminal 127 (120° phase) of the vibrato apparatus. The set of generators 386 are connected to the vibrato apparatus in a manner exactly opposite to the generators 384 while the conductor 189 of the melody tone signal generator 390 is connected to the terminal 123 (240° phase) of the vibrato apparatus

of Fig. 2. Thus the three-tone signal generating sections of the instrument are in 0°, 120°, and 240° phase relation with respect to their vibratos and the instantaneous frequencies of signals of the same nominal pitch produced by these three sets of generators 384, 386, and 390 will therefore be of the character indicated by the curves of Fig. 16 in which the full line curve 397 indicates a tone having vibrato phase of 0°, the dotted curve 398 indicates the instantaneous frequency of a generator 10 having a vibrato phase of 240°, and the dash line curve 399 indicates the instantaneous frequency of a generator 15 having a vibrato phase of 120°. From the curves of Fig. 16 it will be clear that a large number of different frequencies will be present whenever tones of the same pitch 20 from the three sets of generators are simultaneously produced and that when the two sets of generators are played at a time the vibratos thereon will be sufficiently out of phase to produce a considerable chorus effect.

In the various embodiments of the invention previously 25 described the chorus effect is obtained by modulating two or more tone signals of substantially the same pitch or octavely related pitch by signals of the same frequency which are out of phase, or by two or more signals of slightly different frequencies. The chorus effect according to the present invention may however be obtained from but a single musical tone signal source by utilizing apparatus of the kind illustrated in Fig. 18.

In this figure any source 400 of electrical musical tone signals which is deficient in vibrato or chorus, or both, 30 has its output coupled to an artificial transmission line generally in the manner disclosed in my prior Patent No. 2,382,413, but the artificial line usually need not be as long as was desired for the apparatus shown in said patent. The transmission line herein is shown as comprising 35 seven series inductance elements L401 and six shunt capacitors C402 which respectively connect the junctions 404 to 409 to ground. The line is shown as terminating in a suitable impedance R412.

Each of the junctions 404 to 409 is connected to two 40 capacitor plates 414 which are adapted to be scanned by scanner plates 416 and 417, suitably mounted on a shaft 438, 180° apart. The connections between the junctions 404 to 409 and the plates 414 are such that as the plates 416 and 417 are rotated at a constant speed 45 they respectively scan to and fro along the line, all as more fully disclosed in said prior Patent No. 2,382,413. The signals appearing on the scanner plates 416 and 417 are transmitted through slip ring connections (not shown) to amplifiers 418 and 419 having their outputs 50 coupled to speakers 420 and 421.

The scanner plates 416 and 417 are rotated at a suitable vibrato speed, e.g. 7 revolutions per second, and thus the signals picked up by them have vibratos introduced therein in phase opposition to produce the chorus effect. 55 To prevent the production of undesirable tremulant effects and cancellation or partial cancellation of the two signals appearing on the scanner plates 416 and 417 they are amplified by separate amplifiers and translated into sound by separate speakers. The reasons that this is desirable are more fully set forth in my copending application Serial No. 276,731, filed March 15, 1952, now Patent No. 2,830,481. It may be stated here, however, that by virtue of the separation of the signals until they 60 are translated into sound, they add acoustically if in a room having sound reflecting walls, whereas, if they were combined electrically there would be a noticeable, irregular and undesirable tremulant effect. The apparatus of Fig. 18 thus provides means for converting a single musical tone signal into a chorus of signals with the astonishing results heretofore described.

Upon occasion it may be desired to utilize the artificial line vibrato apparatus of said Patent No. 2,382,413 in conjunction with an organ tone signal generating system which does not produce tones with the vibrato and 65 also to employ with said organ a melody section. The

manner in which this may be done and yet obtain the chorus effect is shown in Fig. 19 wherein an organ keyboard 422 is adapted to control the operation of a melody section generator 424, of the type, for example, as shown in Fig. 4, and an organ section 426 which may be of any suitable construction such, for example, as shown in patent to L. Hammond No. 1,956,350. The output of the organ section may be coupled to a non-vibrato amplifier 428 by moving a switch 430 to its full line position, or may be coupled to an amplifier and an artificial line vibrato apparatus 432 by moving the switch 430 to its dotted line position. Both amplifiers 428 and 432 are coupled to a power amplifier 434 the output of which is fed to a speaker 436.

The vibrato apparatus included with the amplifier 432 has a shaft 438 which rotates at the same speed as the scanner of the artificial line vibrato apparatus. An eccentric 440 is secured to the shaft and is adapted to close switch contacts 442 during approximately one half a revolution. When closed, the switch 442 connects a source of direct current potential indicated as +150 v. to the control grid of a triode switch tube 444 through resistors R446 and R447. A resistor R448 is also connected to the control grid through R447 and is connected to a -50 v. terminal of the power supply. A filtering capacitor C450 is connected in parallel with R448. When the switch 442 is open, the triode 444 is biased beyond cutoff, but when the switch is closed the resistors R446 and R448, operating as a voltage divider between the +150 v. and -50 v. terminals, will cause the triode to conduct. The plate of triode 444 is connected to a source of plate current, indicated as a B+ terminal, through a load resistor R452. The plate is also connected to conductor 189 which, it will be recalled from the description of Fig. 4, is connected in the circuit of the melody section oscillator so that potential changes on this conductor will cause the introduction of a vibrato into the output of the melody section oscillator.

Since the cathode of the triode 444 is connected to ground, the triode acts as a switch to apply substantially the full B+ voltage to the conductor 189 through one half revolution of the eccentric 440 while lowering the potential on this conductor nearly to ground during the remainder of the time.

Fig. 19 thus constitutes an exemplary illustration of how the chorus may be obtained from an instrument having two sections, one section in which generators do not lend themselves very satisfactorily to the introduction of the vibrato effect, and the other section being of the oscillator type in which the vibrato may readily be introduced by changing an applied voltage. It will be noted, however, that it is essential that the two vibratos be maintained in opposite phase. This is accomplished by mounting the eccentric 440 in such manner that when the scanner of the artificial line vibrato apparatus (using only one scanner) is scanning the beginning of the line (junction 404), the switch 442 is in closed position. Then as the scanner commences scanning the junctions 405 to 409, causing the output of the amplifier 432 to go flat, the switch 442 is opened and the melody section will go sharp. Of course, this opposite phasing of the vibratos in the signals derived from the two sections of the instrument is maintained throughout operation by virtue of the rigid connection of the eccentric 440 with the scanner shaft 438.

Another embodiment which further illustrates the scope of this invention is shown by the apparatus of Fig. 20. This apparatus is representative of a number of ways by which the chorus may be introduced, using a system involving recording and reproducing means, of which phonographic, sound on film, and magnetic wire or tape recording apparatus are illustrative. Magnetic recording is the method selected for illustration in Fig. 20. In this figure the apparatus comprises a disk 460 which is mounted for rotation with a shaft 462 which, in the ap-

paratus shown, is driven at a speed of six revolutions per second. Thus, if the disk is slightly over three inches in diameter it will have a peripheral linear speed of nearly five feet per second. The disk 460 has an endless wire band or tape 461 on its periphery for co-operation with a signal erasure head 464, a recording head 465, and a pair of reproducing, or pickup, heads 466 and 467.

The erasure head 464 is connected either to a source 468 of superaudio frequency such as an oscillator generating a frequency of 20,000 c.p.s., or to a source of high direct current potential, to erase any previously recorded signal. The recording head 465 is connected to the source 470 of electrical musical tone signals deficient in vibrato, or chorus, or both. The pickup heads 466 and 467 are respectively connected to amplifiers 472 and 473 which supply separate speakers 474 and 475 respectively. The heads 464 and 465 are mounted on a stationary frame 476 while the heads 466 and 467 are mounted for oscillation with respect to the frame by being secured to the ends of arms 478 and 479 respectively, these arms having their other ends pivoted on shaft 462 so that the movement of the heads 466 and 467 will be concentric with the disk 460. The shaft 462 has a pair of similar eccentrics 480 and 481 secured thereto in opposite phase positions. A pair of arms 482 and 483 are mounted for pivotal movement on a stud 485 fixed in the frame 476 and are maintained in contact with the eccentrics 480 and 481, respectively, by means of a spring 485 tensioned between them. The other ends of the frames 482 and 483 have pin and slot connections 486 with the pickup heads 466 and 467 respectively. A tension spring similar to spring 484 may be provided between the arms 478 and 479 to take up any slack by biasing the pickup heads 466 and 467 for movement toward each other.

From the foregoing it will be clear that as the shaft 462, disk 460 and eccentrics 480 and 481 rotate, the eccentrics will, during half of a revolution, move the heads 466 and 467 away from each other and permit movement of these heads toward each other during the remaining half of a revolution. While one head is moving in the direction of rotation of the disk 460, and thus causing the signal picked up by it to be flat, the other head is moving in the opposite direction and causing the signal picked up by it to be sharp relative to the recorded signal. The extent of eccentricity of the eccentrics 480 and 481 need be very slight, in the order of .036 inch, in order to produce a desirable vibrato chorus effect. In order to avoid undesirable tremulant phenomena it is substantially necessary that the outputs of the two pickup heads be amplified and translated into sound through separate channels. This use of separate channels in the outputs of two related signals, as in the apparatus shown in Fig. 18 as well as that shown in Fig. 20, is more fully described and claimed in my said copending application.

Upon frequent occasions it has been proposed that the vibrato effect may be introduced mechanically in instruments in which the tone signal is generated by a continuously moving part or parts (having a tone signal recorded therein, or shaped to represent a tone signal) by oscillating the signal pickup device along the path of movement of the part or parts, as disclosed, for example in my prior Patent No. 2,373,560 as well as in the following patents: Eremeeff No. 2,033,232; Richards No. 2,130,251; Reid No. 2,221,841. The vibrato chorus effect may be introduced in such instruments by providing an additional pickup (or set of pickups) and oscillating the two pickups (or sets of pickups) in opposite phase or at different frequencies, in general in the manner shown in Fig. 20. In some forms of tone signal generators it may be necessary to duplicate the generators and then provide means for oscillating the sets of pickups in opposite phase, or at different rates. In this manner the chorus effect may be obtained. It will be understood that the width of the chorus band of frequencies produced will depend

upon the speed at which this oscillation of the pickups takes place.

The term vibrato is used herein in a rather broad sense to designate the type of frequency modulation employed which, as previously indicated, may be at a rate of between 3.0 and 10.0 c.p.s. or, for rather bizarre effects, may be at a higher rate. The commonly accepted vibrato rate is between 5.5 and 7.5 c.p.s. While the latter sub-audio range is usually preferred for producing the vibrato chorus, it will be understood that the term vibrato is used herein to cover the wider range of modulating frequencies.

From the numerous and variant examples of apparatus and methods in which the invention may be utilized, it will be apparent that the underlying principles thereof are of a fundamental scientific nature which may be briefly stated as follows: The effect of a large number of instruments may be obtained by causing sources of identical or substantially the same frequency to be frequency modulated in opposite polarity phases for a substantial portion of their vibrato periods, so that as one generating source is rising in frequency another source will be falling in frequency.

It is generally believed that the basis for the pleasantness and enjoyment of listeners in the chorus effect resides in the fact that the ear and mind perceive the tone as of unitary pitch, even though it consists of a relatively wide band of frequencies centering about the nominal pitch of the tone being sounded. The physiological reason for the pleasantness of hearing a chorus as contrasted with hearing a single tone probably is based upon the fact that when a single pitch is played the nerve endings which are responsive to the several partials of the tone are continuously excited and become fatigued, whereas as when the acoustic energy is distributed over a large number or band of frequencies, and especially if the energy distribution over this band is not constant, individual auditory nerves (or nerve endings) are not as intensely excited and have a greater opportunity to relax or recuperate. Irrespective of whether this theory is correct, numerous experiments have proved the conclusion to be true.

While I have shown and described particular embodiments of my invention, it will be apparent to those skilled in the art that numerous modifications and variations may be made in the form and construction thereof, without departing from the more fundamental principles of the invention. I therefore desire, by the following claims, to include within the scope of my invention all such similar and modified forms of the apparatus disclosed, by which substantially the results of the invention may be obtained by substantially the same or equivalent means.

I claim:

1. In an electrical musical instrument having an output system, an electrical generator of melody tone signals, a polyphonic tone signal generator, a common manual for controlling the transmission of signals from both generators to the output system, a source of signals of a vibrato frequency having two terminals at which the vibrato signal appears in substantially different phases, and means respectively coupling said terminals to the melody tone generator and the polyphonic signal generator in a manner to cause differently phased vibrato frequency modulation of the tone signals produced by the generators.

2. In an electrical musical instrument having an output system, an electrical generator of melody tone signals, an electrical polyphonic tone signal generator, a common manual for controlling the transmission of signals from both generators to the output system, a source of signals of a vibrato frequency having two terminals in which the vibrato signal appears in opposite phase, and means including said terminals respectively coupling said vibrato frequency source to the melody tone signal generator and the polyphonic tone signal generator in

a manner to cause oppositely phased vibrato frequency modulation of the tone signals produced by both generators.

3. In an electrical musical instrument having an output system, an electrical generator of melody tone signals, an electrical polyphonic tone signal generator, a common manual for controlling the transmission of signals from both generators to the output system, means to effect vibrato frequency modulation of the generator of melody tones, and means to effect vibrato frequency modulation of the polyphonic generator in synchronism with the modulation of melody generator but in a substantially different phase.

4. In an electrical musical instrument having a manual and an output system; a plurality of oscillators one for each note of the chromatic musical scale within the gamut of the instrument, said oscillators generating complex musical tone signals, an apparatus for producing two signals of vibrato frequency but of opposite phase;

5. In an electrical musical instrument having a manual and an output system; a plurality of oscillators one for each note of the chromatic musical scale within the gamut of the instrument, said oscillators generating complex musical tone signals, an apparatus for producing two signals of vibrato frequency but of opposite phase; 10 means coupling alternate octave groups of said oscillators to said vibrato apparatus in a manner to cause said oscillators to generate musical tone signals modulated at the vibrato frequency in one phase; and means coupling the intermediate octave groups of oscillators to the vibrato apparatus in a manner to cause the latter to be vibrato frequency modulated in phase opposite to the first alternate octave groups of oscillators.

6. In an electrical musical instrument having a manual and an output system, first and second ranks of octave

15 groups of oscillators, each rank including an oscillator capable of producing electrical tone signals of the pitch of each note of the chromatic musical scale within the gamut of the instrument, said oscillators generating complex musical tone signals; an apparatus for producing

20 two substantially oppositely phased signals of vibrato frequency; means coupling alternate octave groups of the first rank and the corresponding intermediate octave groups of oscillators of the second rank to said vibrato apparatus in a manner to cause said oscillators to generate musical tone signals modulated at the vibrato frequency in one phase; and means coupling the remaining

25 octave groups of oscillators to the vibrato apparatus in a manner to cause them to be vibrato frequency modulated in phase substantially opposite to that of said alternate octave groups of oscillators of the first rank.

7. In an electrical musical instrument having a manual and an output system, first and second ranks of octave

30 groups of oscillators, each rank including an oscillator capable of producing electrical tone signals of the pitch of each note of the chromatic musical scale within the gamut of the instrument, said oscillators generating complex musical tone signals; an apparatus for producing

35 two substantially oppositely phased signals of vibrato frequency; means coupling alternate octave groups of the first rank and the corresponding intermediate octave groups of oscillators of the second rank to said vibrato apparatus in a manner to cause said oscillators to generate musical tone signals modulated at the vibrato frequency in one phase; and means coupling the remaining

40 octave groups of oscillators to the vibrato apparatus in a manner to cause them to be vibrato frequency modulated in phase substantially opposite to that of said alternate octave groups of oscillators of the first rank.

8. In an electrical musical instrument having a manual and an output system, first and second ranks of octave

45 groups of oscillators, each rank including an oscillator capable of producing electrical tone signals of the pitch of each note of the chromatic musical scale within the gamut of the instrument, said oscillators generating complex musical tone signals; an apparatus for producing

50 two substantially oppositely phased signals of vibrato frequency; means coupling alternate octave groups of the first rank and the corresponding intermediate octave groups of oscillators of the second rank to said vibrato apparatus in a manner to cause said oscillators to generate musical tone signals modulated at the vibrato frequency in one phase; and means coupling the remaining

55 octave groups of oscillators to the vibrato apparatus in a manner to cause them to be vibrato frequency modulated in phase substantially opposite to that of said alternate octave groups of oscillators of the first rank.

9. In an electrical musical instrument having a manual and an output system, first and second ranks of octave

60 groups of oscillators, each rank including an oscillator capable of producing electrical tone signals of the pitch of each note of the chromatic musical scale within the gamut of the instrument, said oscillators generating complex musical tone signals; an apparatus for producing

65 two substantially oppositely phased signals of vibrato frequency; means coupling alternate octave groups of the first rank and the corresponding intermediate octave groups of oscillators of the second rank to said vibrato apparatus in a manner to cause said oscillators to generate musical tone signals modulated at the vibrato frequency in one phase; and means coupling the remaining

70 octave groups of oscillators to the vibrato apparatus in a manner to cause them to be vibrato frequency modulated in phase substantially opposite to that of said alternate octave groups of oscillators of the first rank.

10. In an electrical musical instrument having a manual and an output system, first and second ranks of octave

plifier, a second amplifier, a switch, means for periodically operating the switch in synchronism with the rotary scanning means, common means for driving the scanning means and the switch operating means, means coupling the output of the first signal generating system to the artificial line vibrato apparatus, means coupling the second signal generating system to the second amplifier, means controlled by the switch for introducing a vibrato frequency modulation in the output of the oscillator effectively in phase opposition with respect to that introduced by the artificial transmission line vibrato apparatus, and means for coupling the outputs of the amplifiers to the output system of the instrument.

9. In an electrical musical instrument having a manual and an output system; a plurality of octaves of oscillators for producing electrical complex musical tone signals for the notes of the chromatic musical scale within the gamut of the instrument; an apparatus for producing two signals of vibrato frequency but of opposite phase; means coupling the oscillators of alternate octaves to said vibrato apparatus in a manner to cause the oscillators to generate musical tone signals modulated at the vibrato frequency in one phase; means coupling oscillators of intermediate octaves to the vibrato apparatus in a manner to cause the latter to be vibrato frequency modulated in phase opposite to the oscillators of the first alternate octaves, and means coupling the outputs of all of the oscillators to the output system.

10. In an electrical musical instrument having a manual and an output system; first and second ranks of octave groups of oscillators, each rank including an oscillator capable of producing electrical musical tone signals of the pitch of each note of the chromatic scale within the gamut of the instrument, said oscillators generating complex musical tone signals; an apparatus for producing two substantially oppositely phased signals of a vibrato frequency; means coupling the inputs of oscillators of alternate octaves of the first rank and corresponding oscillators of intermediate octaves of the second rank to said vibrato apparatus in a manner to cause said oscillators to generate musical tone signals modulated at the vibrato frequency in one phase; means coupling the inputs of the oscillators of the other octaves to the vibrato apparatus in a manner to cause them to be vibrato frequency modulated in phase substantially opposite to that of the oscillators of said alternate octaves of the first rank; and means for coupling the outputs of all of the oscillators to the output system.

11. The method of producing a chorus tone signal from a single complex wave electrical musical tone signal which comprises, frequency modulating a first portion of the signal at a vibrato rate in one phase, and frequency modulating another portion of the signal at a vibrato rate but in phase substantially different from the modulation of the first portion of the signal.

12. In an electrical musical instrument having a plurality of ranks of electrical tone signal generators, a source of modulating vibrato frequency having at least three terminals at which the modulating frequency is present in substantially different phases, means coupling alternate octaves of a first rank of generators to the first of said terminals and the intermediate octaves of generators to the second of said terminals, means coupling alternate octaves of a second rank of generators to the second of said terminals and the intermediate octaves of generators to the first of said terminals, means coupling alternate octaves of a third rank of generators to the third terminal and the intermediate octaves of generators to the first terminal, all of the coupling means being of a character effective to cause frequency modulation of the generators, an output system, and manually operable means to cause selected generators to supply signals to the output system, whereby a chorus effect will be obtained whenever unison tones derived from different ranks of

generators are sounded and whenever octave tones derived from the same rank of generators are sounded.

13. The method of producing the effect of a large chorus of tone signals from two sources of complex tone signals having high amplitude fundamentals or partials of substantially the same musical pitch within an audio frequency range of between thirty-two cycles to fifteen thousand cycles per second which comprises, frequency modulating the signals from the two sources at a vibrato rate of between three and fifteen cycles per second and to a vibrato extent, but in opposite phase so that while the pitch of one signal is increasing that of the other is decreasing, and vice versa.

14. The method of producing a chorus effect which comprises, for a substantial controllable time interval, modulating electrical musical tone signals having partials of the same musical pitch in the audio frequency range of from thirty-two cycles to fifteen thousand cycles per second, by vibrato frequencies which are derived from the same source and which are substantially out of phase.

15. The method of producing the effect of a chorus of a large number of sources from two electrical generators of complex musical tone signals which respectively include frequencies which are of the same musical pitch in the audio frequency range of from thirty-two to fifteen thousand cycles per second, which comprises causing the signal from one of the generators to change at a vibrato rate in a sharp direction while causing the signal from the other generator to change in a flat direction at the same vibrato rate, and vice versa, during a substantial portion of the time that the generators are producing signals.

16. In an electrical musical instrument having an output system, a plurality of octaves of complex wave musical tone signal generators forming a single rank and producing signals of the nominal frequency of the tempered musical scale, a manual comprising a plurality of keys for controlling the transmission of signals from the generators to the output system, means for producing two different vibrato frequency modulating signals, and means coupling said vibrato means to the generators so that generators of adjacent octaves are modulated by different vibrato signals.

17. In an electrical musical instrument having an output system, the combination of two independent complex wave electrical tone signal generating sources in which the tone signals include partials of the same nominal musical pitch, unitary means for frequency modulating said generators at the same rate, said means being operative to frequency modulate one of said sources to be sharp relative to its nominal pitch while at the same time modulating the other of said sources to be flat relative to its nominal pitch, means coupling the outputs of said sources to the output system, and means in said output system for translating the signals from both of said generators into sound.

18. In an electrical musical instrument, the combination of an output system including electroacoustic translating means, two independent electrical musical tone signal generators having a partial of the same nominal musical pitch which may be varied over a vibrato frequency range, a vibrato frequency source having two terminals on which the vibrato signal appears in opposite polarity, means respectively coupling the generators to said terminals thereby to frequency modulate one tone signal generator in one sense while frequency modulating the other generator in the opposite sense to create a chorus effect when the outputs of said generators are simultaneously perceived by a listener, and means for coupling the outputs of the generators to the output system.

19. The combination set forth in claim 18 in which said electrical generators generate complex musical tone signals of octavely related pitches.

20. The method of producing a chorus musical tone signal from a single source of complex electrical musical tone signals having a nominal pitch within the range of thirty-two cycles to fifteen thousand cycles per second, which comprises transmitting the signal through an artificial electrical transmission line, scanning said line by two pickups operating effectively to and fro at the same vibrato speed but in substantially opposite phase, and separately amplifying and translating into sound the signals induced in the pickups.

21. Means for producing a chorus effect comprising, two sources of complex electrical musical tone signals each having a partial of the same nominal pitch, means for modulating for controllable substantial intervals of time the two complex electrical musical tone signals by vibrato frequencies in the range of from three to fifteen cycles per second, such that the modulation of one of the partials of one of the signals is of phase substantially opposite to that of the partial of corresponding pitch of the other during substantial portions of the vibrato cycle, and means for translating the resulting electrical tone signals into sound.
